UNITED STATES PATENT OFFICE.

RICHARD MARTIN, OF OAKLAND, CALIFORNIA, ASSIGNOR TO NATIONAL BRIQUETTE COMPANY, OF SAN FRANCISCO, CALIFORNIA, A CORPORATION OF CALIFORNIA.

BUCKET CONVEYER.

No. 835,798.

Specification of Letters Patent.

Patented Nov. 13, 1906.

Application filed April 16, 1906. Serial No. 311,837.

To all whom it may concern:

Be it known that I, RICHARD MARTIN, a citizen of the United States, residing at Oakland, Alameda county, State of California, have invented certain new and useful Improvements in Bucket Conveyers; and I hereby declare the following to be a full, clear, and exact description of the same.

My invention relates to the class of bucket conveyers; and it consists in the novel bucket and the means for assembling and operating a plurality thereof in an endless system forming a conveyer, adapted for use especially in the handling of soft and sticky materials.

The object of my invention is to provide a conveyer in which the buckets are designed to positively discharge their contents by a self-clearing action independent of and supplemental to gravity, whereby they are relieved and cleansed of all material, no matter how soft or adhesive it may be.

Referring to the accompanying drawings, Figure 1 is a side elevation of my bucket conveyer. Fig. 2 is a front view of one of the buckets, showing the swinging sector projected through the base to full bucket capacity. Fig. 3 is a front view of one of the buckets, showing the face of the base through which the sector has been withdrawn in its self-clearing action.

The bucket consists of a swinging sector 1 and a relatively fixed base 2. The sector is open at its ends, and its sides and perimeter play through slots 3 in the base 2 as the sector swings on its center 4, which latter is a pivot in lugs 5 on the back of the base 2. These lugs 5 are best extended to form guiding-flanges 6 for the sides of the sector 1 in their movement through the slots of the base 2. The relation of the several parts is such that when the sector 1 is projected from the face of the base 2 until its sides are limited in the ends of the side slots in the base said sector and base form an open-mouthed cavity or bucket bounded by the base for a bottom and by the sides and perimeter of the sector for the remaining walls.

By causing the sector to withdraw from the face of the base and project itself from the back thereof the effect is to diminish the capacity of the cavity or bucket until it dis-

appears and nothing is left but the plane surface of the base on that side. It is therefore obvious that the contents of the bucket must by this action be positively discharged and the bucket effectually cleared of everything under the resistant pressure and scraping of the relatively fixed base. Now by assembling a plurality of these buckets in an endless chain or system and providing means for swinging the sectors 1 of the buckets through their bases 2 a conveyer may be provided the buckets of which will be self-clearing or self-cleansing, and such conveyer may be employed for a variety of useful work, especially in handling soft and sticky material. Accordingly I illustrate one form of such conveyer, which may stand as a type embodying the principle stated. In this conveyer, 7 represents a frame in the ends of which are terminal sheaves or sprockets 8, to which any suitable power may be applied. The adjacent ends of the bucket-bases 2 are connected by links 9, thus furnishing the spaces for the engagement of the sprockets. Pressure to swing the sectors of the buckets is applied at their free inner angles, where suitable anti-friction-rollers 10 are mounted. Regarding the right-hand end of the conveyer as that at which the buckets are projected and held in working position and the other end as that at which the dumping of the load is to take place, I have the following arrangement of tracks necessary to this end: Around the right-hand sheave the track 11 is concentric with the sprocket or parallel with the line of travel of the buckets, and thence said track continues from the upper side of the sprocket in a straight course, as shown at 12, still parallel with the line of travel. On these tracks 11 and 12 the rollers 10 of the bucket-sectors travel, and the location of the tracks is such that said sectors are held forwardly from their bases, thus presenting the full capacity of the buckets for first acquiring their load and, second, carrying it forward.

The track 12 terminates near the upper extremity of that diameter of the left-hand sprocket which is transverse to the path of travel of the buckets, and just beyond the plane of this diameter begins the eccentric track 13, the entrance to which is above the line of the rollers 10 of the sectors, so that

said rollers upon leaving the track 12 pass within or under said track 13. The eccentricity of this track to the curved path of travel of the buckets is such that by pressure on the rollers 10 the sectors are gradually withdrawn from the face of their bases and swing inwardly through them to their backs. This movement continues as the buckets travel around the sprocket until on the opposite side of said sprocket they are fully withdrawn, as shown. In this movement their contents must of course be forced out by their base and discharged. What little material may stick to the face of the base of the bucket may be scraped off by a fixed wire 14. To bring the bucket-sectors back again to operative position, an inclined track 15 starts at or about the end of track 13, and the rollers 10 pass under this track. The track 15 inclines outwardly toward the path of travel of the bases, and thereby forces the sectors out again until they reach their outward limit, where the said track 15 may join the track 11. It will be understood that these tracks are carried by suitable supporting devices from the frame 7 and that in practice the sprockets and tracks will be in pairs to equalize the pressure on both sides of the buckets. Such constructive details I have not deemed it necessary to show, as they will be readily understood.

I do not confine myself to the specific tracks here shown as a means for swinging the bucket-sectors, as other forms of tracks, cams, and pressure devices may be employed, the essential feature in this regard being the provision of means for operating the swinging sectors at the proper times.

Having thus described my invention, what I claim as new, and desire to secure by Letters Patent, is—

1. In a conveyer, a bucket comprising a relatively fixed base, and a swinging sector playing through said base and adapted to be projected from the face of said base to complete the bucket-cavity, and withdrawn therefrom to discharge the load.

2. In a conveyer, a bucket comprising a relatively fixed base, and a swinging sector pivoted to the back of said base and playing through the base, whereby it may be projected from the face of the base to complete the bucket-cavity, and withdrawn therefrom to discharge the load.

3. In a conveyer, a bucket comprising a relatively fixed base having on its back suitable lugs for a pivot and guide-flanges extending from said lugs, and a swinging sector pivoted to said lugs and guided by said flanges, said sector playing through the base, whereby it may be projected from the face of the

base to complete the bucket-cavity, and withdrawn therefrom to discharge the load.

4. A bucket conveyer consisting of a chain of pivotally-connected buckets, each comprising a relatively fixed base and a swinging sector playing through said base, means for mounting and driving said chain, and pressure devices for forcing said sectors to play through their bases. 65

5. A bucket conveyer consisting of a chain of pivotally-connected buckets, each comprising a relatively fixed base and a swinging sector pivoted to the back of the base and adapted to play through the base, whereby it is successively projected from the face of the base and withdrawn therefrom, means for mounting and driving the chain, and pressure devices for forcing said sectors to play through their bases. 70

6. A bucket conveyer consisting of a chain of pivotally-connected buckets, each comprising a relatively fixed base and a swinging sector playing through said base, means for mounting and driving said chain, and pressure devices for forcing said sectors to play through their bases consisting of suitably-disposed tracks upon which the sectors impinge. 75

7. A bucket conveyer consisting of a chain of pivotally-connected buckets, each comprising a relatively fixed base and a swinging sector pivoted to the back of the base and adapted to play through the base, whereby it is successively projected from the face of the base and withdrawn therefrom, means for mounting and driving the chain, and pressure devices for forcing said sectors to play through their bases consisting of suitably-disposed tracks upon which the sectors impinge. 90

8. In a conveyer, a bucket comprising a relatively fixed base, and a swinging sector playing through slotted portions of said base and adapted to be projected through said slotted portions to complete the bucket-cavity and withdraw therefrom to discharge the load. 105

9. In a conveyer, a base portion having a plurality of slotted portions, and a series of swinging bucket-sectors, one on each slotted portion of the base, the said buckets being adapted to be projected through said slotted portions of the base to complete the bucket-cavity and withdraw therefrom to discharge the load. 110

In witness whereof I have hereunto set my hand.

RICHARD MARTIN.
